DEVICE FOR FOLDING PAPER BOARD BLANKS
 Hans Blumer, Zurich, Switzerland, assignor to Steiger
 A.G. Lithographie, Druckerei, Cartonnagefabrik, Bern,
 Switzerland

Filed June 13, 1960, Ser. No. 35,625
 Claims priority, application Switzerland June 18, 1959
 7 Claims. (Cl. 93—51)

This invention relates to improvements in means for erecting boxes from paper or cardboard blanks and, in particular, is directed to a new and novel device for folding blanks into rectangular type boxes.

The device of the present invention is particularly, though not exclusively, designed for folding a box having a rectangular bottom, upstanding opposed end walls and upstanding opposed side walls, the side and end walls being connected to the bottom by fold lines. The box, further, includes a tab on the ends of each side wall, the tabs being connected thereto by hinge lines and being positionable at right angles to the side walls and extending inwardly toward the end walls. The tabs terminate at their free ends in upstanding locking projections and are adapted to be positioned through vertical slots formed in the end walls adjacent the end portions thereof. The end walls are also provided with upwardly projecting flaps which are connected by fold lines to the upper edges of the end walls. The flaps extend above the coplanar upper edges of the end walls and the side walls and are adapted to be folded over under a lid or cover which is hingedly carried by the upper edge of one of the side walls. The slots extend into the flaps and the locking projections fit through the slots in the flaps and are adapted to be folded over when the flaps are bent over under the cover.

The device of the present invention comprises a stationary part and a die or moving part cooperating therewith. The stationary part provides a rectangular opening through which the die passes in erecting the box from a blank. The stationary part includes a first pair of parallel, laterally spaced bending rails and a second pair of parallel, laterally spaced bending rails, the rails of the second pair being disposed at right angles to the rails of the first pair and being positioned in vertically spaced relation thereto. The upper pair serves to bend over the end walls provided with slots and the tabs of the side walls. The upper pair of rails carries a plurality of spring urged balls which are disposed normal to the path of movement of the die and which are positioned in depending relation to the rails of the first pair. Certain of the balls are arranged directly below the bending rails of the upper pair and serve to push the portions of the end walls that lie outside of the slots into corresponding recesses in the die so as to open the slots. The rails of the lower pair serve to fold up the side walls and force the tabs into the slots. Certain of the balls lie substantially well below the rails of the first pair and substantially in the plane of the rails of the second pair. They serve to counteract the tendency of the holding projections to slip out of the slots.

Thus, the primary object of the present invention is to provide a device for easily and quickly folding cardboard blanks into box formations by causing the foldable side and end walls to be folded into erected positions and locked in their box form.

A further important object of the present invention is to provide an adjustable structure wherein the rails are interconnected and are joined in an adjustable manner so that the rails of each pair can be moved laterally closer or apart and the pairs of rails can be vertically spaced in an adjustable manner whereby boxes of various sizes can be erected.

2

The foregoing and ancillary objects are attained by this invention, the preferred embodiment of which is set forth in the following description and illustrated in the accompanying drawing, wherein:

5 FIGURE 1 is a perspective view of one form of box erected by the device of this invention;

FIGURE 2 is a vertical sectional view of the box erecting device and is taken on line 2—2 of FIGURE 3;

FIGURE 3 is a top plan view of the box erecting device;

10 FIGURE 4 is a vertical cross-sectional view taken on line 4—4 of FIGURE 3, and,

FIGURE 5 is a detailed vertical sectional view of the interconnecting means between the pairs of bending rails 15 and is taken on line 5—5 of FIGURE 4.

Referring now more particularly to the drawings and, initially to FIGURE 1, the box, which is representative of the type of boxes for which the present device has been designed, includes a rectangular bottom 1 and opposing side walls 2 and opposing end walls 3. The side and end walls are connected with the bottom by fold lines. Each of the side walls has at its ends a tab 4 which is hingedly connected thereto and which is positionable at right angles inwardly towards the end walls. Each tab is provided at its free end with an upstanding holding projection 5. The end walls 3 are provided, adjacent their outer ends, with vertical slots which are adapted to receive the tabs 4 and projections 5. The end walls are provided at their upper edges with flaps 3b which are connected to the upper edges by fold lines. The flaps are adapted to lie under the cover or lid, when the cover is closed and the flaps fold over the projections 5 to lock the tabs securely in the slots.

The device for erecting the box of FIGURE 1 is shown 35 in FIGURES 2—5 and includes a stationary part A and a die or moving part B which cooperates therewith for erecting the side and end walls 2 and 3 of the box. The stationary part provides a rectangular opening through which the die passes, the die being moved in the direction

40 of the double arrow 7 by suitable means (not shown).

The stationary part A includes a first pair of bending rails 8, 8 and a second pair of bending rails 9, 9. The bending rails 8, 8 are spaced laterally apart and are disposed in parallel relation while the bending rails 9, 9 are also spaced laterally apart in parallel relation.

45 The bending rails 9, 9 are disposed vertically below the bending rails 8, 8 and are positioned in right angular relation thereto. The bending rails are spaced apart in an adjustable manner depending upon the height of the box to be erected and are spaced vertically apart in the direction 50 of motion of the die B.

The bending rails are curved at their inner faces so as to easily receive and fold up the walls of the box as the box is moved through the opening of the stationary part in contact with the curved inner faces of the bending rails.

Each of the bending rails is formed on its outer side with a longitudinally extending dove tail groove 10. Connecting links 14 are disposed between the upper pair 60 of rails and the lower pair of rails and are mounted as shown in FIGURE 5. Thus, the links are mounted in the dove tail grooves by means of interior clamping members 11 and screws 13. The connecting links are also connected to the lower rails 9 which have dove tail

65 grooves 10 by means of the interior clamping members 16 and screws 15. The screws 15 pass through vertical slots 15a in the connecting links, as shown in FIGURES 4 and 5, so that the vertical distance between the upper pair of rails and the lower pair of rails can be adjusted.

70 Thus, it can be seen that the width and length of the rectangular opening in the stationary part which is defined by the upper pair of bending rails and the lower pair

of bending rails can be adjusted so as to accommodate different sizes of blanks. The vertical space between the upper pair of bending rails and the lower pair of bending rails can also be adjusted so as to be substantially equal to the height of the box to be erected.

A first pair of spring urged balls 17 and 18 is positioned directly below each of the bending rails 8 of the upper pair, as can be seen in FIGURES 2 and 4. The balls 17 and 18 are spaced apart and are disposed adjacent the inner surfaces of the bending rails 9, 9, as shown in FIGURE 4. A second pair of spring urged balls 19 and 20 is disposed below each of the bending rails 8 and the balls 19 and 20 are positioned at a height substantially equal with the lower edges of the lower bending rails. The balls 19 and 20 are positioned between the balls 17 and 18 and are substantially close together.

As shown in detail in FIGURE 2, each of the balls is guided in a sleeve 21 which is screwed onto a screw bolt 22 and secured by means of a lock nut 23. The screw bolts 22 are mounted in apertures in supporting straps 24 and 25 and held in place by lock nuts 26. The straps 24 are provided for the balls 17 and 18 while the longer straps 25 are provided for the balls 19 and 20, as can be seen in FIGURE 2.

By displacing a sleeve 21 along a screw bolt 22 it is possible to modify the pressure exerted by the coil spring 30 on the balls, the balls being held from complete urged out of the sleeves by the slightly inwardly bent outer ends of the sleeves, as shown in FIGURE 2. The coil spring seats against the outer ends of the bolts.

The straps 24 and 25 are attached, as shown in FIGURE 2, to the upper rails by means of clamping members 29 which are mounted in the dove tail grooves in the upper rails, clamping and guide members 28 and screws 27. A strap can be adjusted by loosening a screw 27 so as to be displaced along the axis of a rail 8. The straps are adjustable to position the balls along the rails depending upon the size of a box to be erected.

In using the device, a paper board blank is first placed by hand or by suitable mechanical means upon the upper bending rails in such a way that it is centered with the die B. In other words, the bottom wall of the blank 1 is positioned so that it covers the opening in the stationary part A. As the die moves downwardly, the end walls 3 and tabs 4 are first bent upwardly by being moved against the bending rails 8. As soon as the bottom wall 1 comes within the range of the lower bending rails 9, 9, the portions 3a of the end walls, which lie outside the slots 6, will be in the range of action of the balls 17 and 18 which then operate to push the portions 3a inwardly into the concave recesses 31 of the lateral faces of the die facing the same, as shown in FIGURE 2. Thus, the slots 6 are open. While the balls 17 and 18 are still active to keep the slots 6 open, the side walls 2 come within the range of the lower bending rails 9, 9. As these side walls 2 are being erected, the tabs will slide from under the balls 17 and 18 into the slots 6. This operation is substantially terminated as soon as the base portion or bottom wall 1 reaches the lower edge of the lower bending rails 9, 9. At this point, the balls 19 and 20 push the flaps 3b inwardly to bend them about the fold lines 3c. The flaps 3b and the holding projections 5 are thereby bent inwardly about the folding lines 3c.

While the preferred form of the present invention has been shown and described herein, other forms can be realized as come within the scope of the appended claims.

I claim:

1. A device for erecting of paper board boxes of the

type having a rectangular bottom and a pair of opposing end walls and a pair of opposing side walls, said walls being connected to the bottom by fold lines, each of said side walls having a tab positionable at right angles thereto to extend inwardly toward the end walls and having a locking projection and the end walls having vertical slots to receive the tabs and projections and having upper edges provided with hinged flaps into which the slots extend; said device comprising a stationary part having an opening and a die movable in a rectilinear path through the opening to erect the box from a flat blank, said stationary part including a first pair of bending rails disposed in parallel, laterally spaced relation and second pair of bending rails disposed in laterally, spaced parallel relation, the second pair of rails being vertically spaced below the first pair and being in right angular relation thereto, the upper pair of bending rails serving to bend over the end walls and the tabs of the side walls, and a plurality of freely rotatable spring urged balls lying below the first pair of rails in substantially the same vertical planes and being mounted to move transversely to the direction of movement of the die, certain of said balls being arranged intermediate the rails of the first and second pair and being adapted to push inwardly the portions of the end walls that are outside the slots into corresponding recesses in the die in order to open the slots to receive the tabs, said tabs being moved into the slots by the bending rails of the second pair which serve to fold up the side walls and certain of said balls being disposed at a level substantially below the lower pair of bending rails to bend the flaps down and lock the tabs in place by bending over the projections.

2. The combination of claim 1, wherein said bending rails of each pair are laterally adjustable relative to each other.

3. The combination of claim 1, wherein the first and second pairs of bending rails are mounted for vertical adjustment.

4. The combination of claim 1, wherein the bending rails of the first pair are connected to the bending rails of the second pair by connecting links and means mounting the links for vertical adjustment relative to the pairs of rails and for adjustment along the longitudinal axes of the rails of each pair.

5. The combination of claim 1, wherein the spring urged balls are mounted in holders carried by straps that depend from the rails of the first pair, said straps being adjustable vertically and along the axes of the rails of the first pair.

6. The combination of claim 5, wherein the holders include means for adjusting the spring tension on the balls.

7. The combination of claim 1 wherein each of the spring urged balls is mounted in an outer end of a tubular holder with the inner end of the tubular holder being threaded onto a support member, and the spring urging the ball being disposed within the tubular holder between the ball and the support, with the adjustment of the tension of the spring being accomplished by rotating the tubular holder with respect to the support.
